UNITED STATES PATENT OFFICE.

WILLIAM ROEMER, OF NEWARK, NEW JERSEY.

BAG OR SATCHEL FRAME.

SPECIFICATION forming part of Letters Patent No. 378,263, dated February 21, 1882.

Application filed March 30, 1887. Serial No. 232,987. (No model.)

To all whom it may concern:

Be it known that I, WILLIAM ROEMER, a citizen of the United States, residing at Newark, in the county of Essex and State of New Jersey, have invented certain new and useful Improvements in Bag or Satchel Frames; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention relates to that class of bag-frames, shown in my prior application, Serial No. 216,812, in which the jaws of the bag are pivoted upon the opposite ends of certain bars or rods disposed at the ends of the bags, at the 20 top thereof, so that there is formed, when the jaws are open, a very wide passage to the pocket or chamber in the bag equal to or approximating in length and breadth the length and breadth of the bag-body.

25 The object of this invention is to reduce the cost of manufacture, to facilitate the construction, and to secure certain effects of finish not common to other bags now in the market.

The invention consists in the combination 30 and arrangement of parts, substantially as will be hereinafter set forth.

Referring to the accompanying drawings, comprised in three sheets, in which like letters of reference indicate corresponding parts in 35 each of the several figures, Figure 1 is a side elevation of the improved bag, showing the jaws closed. Fig. 2 is a plan of the frame detached from the body material, said jaws being open. Fig. 3, Sheet 2, is a plan of said 40 jaws in their closed relation and separate from the body of the bag, and also being devoid of covering-leather. Figs. 4 and 5 are side elevations of said jaws detached from central or end sections. Fig. 6 illustrates a blank from which 45 certain side flanges are formed. Fig. 7 is a detail side elevation of said central or end sections. Fig. 8 is an elevation of a portion of the inner of the two jaws, and Fig. 9 is an elevation of a portion of the outer of said jaws. 50 Fig. 10, Sheet 3, is a section taken on line X, Fig. 2; and Fig. 11, an inside view of a portion of one of said jaws.

In said drawings, *a* indicates the body of the bag or satchel, at the opposite ends of which are arranged end sections, *b b*, of the frame, 55 said sections being flat strap-like pieces vertically disposed and perforated at their opposite ends to receive the inner and outer jaws, said perforated ends providing pivotal bearings for said jaws. Said jaws, when pivoted on said 60 central sections, are so constructed that when closed together one overlaps the other, as indicated in Fig. 3.

The jaws pass one over the other when the two are folded together. The overlying one 65 I shall, for convenience in description, term an "outer" jaw, *c*. The remaining one I shall term the "inner" one, *c'*. The said outer jaw consists, more especially, of a longitudinal section, *d*, upon which the ordinary lock-case 70 and handle-rings find bearings. Said longitudinal section is formed of one or two pieces of sheet metal, and is preferably bent longitudinally, as indicated in Fig. 10, forming a seat, *d'*, for said lock-case, and a vertical portion, *d''*, to raise the lock-case seat above the level of the upper portion of the bag, as indicated in Fig. 1, and also to give stiffness and strength to said longitudinal portion. Said section is also bent at right angles or approximately at right angles to the said vertical portion *d''*, and extends longitudinally 75 across the bag with said vertical portion to form a flange, *d''*, which is preferably perforated along its edge, as in Figs. 3 and 11, to receive the bag material and allow of its being sewed or riveted to the body material, the said flange when bent as described and having the leather body material thereon extending under said material and supporting the same, so 80 that it will lie in about the same plane therewith. At the opposite end of the longitudinal portion of the outer jaw are secured short side flanges or end sections *f* of the jaw, which extend from said longitudinal portions 85 *d* and connect the same with the ends of the end sections *b b*, so that the said parts *d f f* may together work pivotally on the said sections *b b*. The said end sections *f f* of the jaws, which are preferably riveted upon the 90 longitudinal section, as at *g*, and connect said longitudinal section rigidly with the said end sections *b b*, or so there will be no independent movement between or of the parts, are of 95 100

sufficient length to bring the longitudinal sections of the jaws to about the middle of the upper part of the bag when closed down thereon, and when thus closed lie parallel with 5 the portions of the end bars $b b$, lying thereunder.

When the jaws of the frame are closed together, said end sections of the jaws will longitudinally cover said end sections and conceal 10 the same from view. Said side flanges are preferably of a single piece of metal, and are formed from the blank substantially such as shown in Fig. 6. Said blank is bent at about the lines f' and f'' , Fig. 6, forming pivotal ears 15 f^3 and f^4 , which lie in parallel planes, and provide bearings for the pivot i , which connects said side flanges with the central or end sections b .

The extremities of the longitudinal portion 20 of the outer jaw extend slightly beyond the ears f^4 of the side flanges, being bent down and out, as at j , forming a slight opening therebetween, as in Fig. 9, to allow for the body material of the bag.

25 The inner jaw, c' , is of similar construction to that of the outer jaw, excepting that the longitudinal section is made somewhat smaller than that of the outer jaw, and has no outwardly and downwardly extending portions 30 corresponding to those marked j .

The ends of the longitudinal pieces of the inner jaw are so formed that both the ends of the flange d^3 and the elevated portions corresponding to the seats d' will lie in a plane, and 35 thus together bear against the upper face, f^5 , of the side flanges, as indicated in Fig. 4, the elevated portion d' being rounded down at the ends, as in Fig. 8, and then bent on a plane with the flange d^3 , as at d^6 , to secure a proper 40 result. In the outer jaw the ends $d^7 d^8$ do not preferably lie in the same plane with the ends of the flange d^3 , but lie a little above to allow for the cover-leather of the jaw beneath.

Having thus described my invention, what I 45 claim as new is—

1. In a bag or satchel frame, the combination, with end sections $b b$ of a frame, of jaws $c' c'$, pivoted at the opposite ends of and connecting said end sections, each of said jaws 50 consisting, essentially, of a seat, d' , a vertical portion, d^2 , to elevate said seat, and a perforated flange, d^3 , to receive the body material, and end sections $f f$, secured to the ends of said section d , and provided with ears $f^3 f^4$, 55 pivoted on the end sections $b b$ of the frame, substantially as set forth.

2. In combination with jaws $c' c'$ of a bag-frame, strap-like end sections $b b$, disposed vertically edgewise at the ends of the frame and providing pivotal bearings for said jaws, 60 substantially as and for the purposes set forth.

3. In combination, in a bag-frame with end bars or sections $b b$, providing pivotal bearings, jaws $c' c'$, consisting of longitudinally-bent portions d , and sections $f f$, secured at 65 the ends of said longitudinally-bent portions, providing ears $f^3 f^4$, said parts being arranged and combined substantially as and for the purposes set forth.

4. In a bag-frame substantially such as described, the combination, with end sections $b b$, of jaws $c' c'$, provided with sections $f f$ at the ends thereof, said sections $f f$ being each of a single piece bent to form ears $f^3 f^4$, substantially as described. 70

5. In a bag-frame substantially such as described, a jaw combining therein end sections $f f$, and a longitudinal section, d , having flanges d^3 , a vertical portion and an elevated seat, the last being rounded down at the extremities of said section d , and bent to lie flush or approximately flush with the ends of said flange d^3 , substantially as herein described. 80

6. In a bag-frame substantially as described, end sections $b b$, jaws $c' c'$, with end sections $f f$, 85 rigidly secured to and connected by longitudinal parts or sections d , and pivotally secured upon the extremities of the said sections $b b$, and adapted to lie, when in their closed positions, parallel with said end sections $b b$, the 90 said longitudinal section d having a seat, d' , raised above the said sections $f f$ when in said closed positions, substantially as and for the purposes set forth.

7. In a bag-frame, the combination of end 95 bars or sections $b b$, longitudinal sections $d d$, and end sections $f f$, connecting said longitudinal sections with said end sections $b b$, being pivotally secured upon said end sections $b b$, as at i , and the longitudinal sections being 100 raised above the sections $f f$ to form a raised seat at the center of the closed bag, substantially as set forth.

In testimony that I claim the foregoing I have hereunto set my hand this 25th day of 105 March, 1887.

WILLIAM ROEMER.
